OTTO JULIUS SWENSON, OF LOS ANGELES, CALIFORNIA, ASSIGNOR OF ONE-HALF TO
HARRY ELDON BEAM, OF LOS ANGELES, CALIFORNIA.

MASSAGING DEVICE.

1,239,539.

Specification of Letters Patent. Patented Sept. 11, 1917.

Application filed December 16, 1916. Serial No. 137,388.

To all whom it may concern:

Be it known that I, OTTO JULIUS SWENSON, a citizen of the United States, residing at Los Angeles, in the county of Los Angeles and State of California, have invented new and useful Improvements in Massaging Devices, of which the following is a specification.

This invention relates to massaging devices, and it has for its object to provide an improved massaging device for general massaging purposes having advantages not possessed by devices of this general nature as heretofore constructed, and whereby an operator may beneficially treat a patient, or the patient may massage portions of the body, and which will have inherent qualities for producing beneficial results.

In accordance with the invention, a plurality of rotatable bodies are suitably grouped for presentation to the body of the patient or the user, to be pressed against the body and moved as with a reciprocatory motion contacting, with the body at spaced points and so that in the movement of the massaging device the rotating bodies will be caused to properly traverse the portions of the body being massaged with consequent stimulation and increase of circulation at the treated portions of the body. The rotating bodies are preferably mounted between a pair of plates through one of which such rotating bodies protrude and such rotating bodies are preferably magnetized as is the apertured plate through which they protrude, while the other plate is preferably of non-magnetic material.

A further object of the invention is to provide a device of the general nature stated, which will be relatively simple and inexpensive in construction and organization when the superior results attendant upon its use are considered, and which may be readily taken apart so that rotating bodies or other portions of the device may be cleansed after each use of a device organized in accordance with the invention, and that the magnetic parts of the device may be re-magnetized when, due to loss of magnetism, such re-magnetization becomes necessary.

With the above and other objects in view, the invention consists in the novel and useful provision, formation, association and relative arrangement of parts, members and

features, all as hereinafter set forth, shown in the drawing, and finally pointed out in claims.

In the drawing:

Figure 1 is a central vertical sectional view of a massaging device constructed and organized in accordance with the invention;

Fig. 2 is a sectional view taken on the line x^2-x^2 , Fig. 1, and looking in the direction of the appended arrows; and

Fig. 3 is a fragmentary end elevation of the device shown in the other figures.

Corresponding parts in all the figures are designated by the same reference characters.

Referring with particularity to the drawing, in the embodiment of the invention therein shown, A designates, in each instance, a rotatable element adapted for contact with the body, B designates a cage or body for properly spacing the elements A and whereby the same may be caused to traverse portions of the body in properly spaced relation, and C designates handle means whereby the body B and the spaced elements A may be manually manipulated.

Each of the elements A preferably comprises a spherical body 4, and the cage or body B preferably comprises a lower apertured member of sheet magnetic metal 5, and an upper member 6 of preferably non-magnetic material. The member 5 is provided with spaced apertures at 7 to permit the projection of the spherical members 4 therethrough, to the desired extent only, and the member 6 is formed with cup portions 6^a opposite each of such apertures 7 and in each of which one of the rotatable spherical members 4 is seated or has a bearing.

The member 5 is upturned at its forward end as at 5^a so that it extends into the plane of the member 6, and the upturned portion of such member 5 is provided with a plurality of apertures at 5^b and 5^c, which apertures are adapted to receive, respectively, in hooked engagement, tongues 6^b and 6^c provided at the forward portion of the member 6. The other end of the member 5 is upturned and cut away to form a post 8, which post is received in a notch 9 provided in the member 6, latch means α being provided for maintaining the parts in assemblage. Such latch means α may comprise a tubular member 10 secured to the member 6, a bolt 11 in such tubular member, a spring 12, and a notch 13 provided in the 110

post 8 and into which the bolt 11 is adapted to take. The spring 12 acts against a shoulder 11^a on the bolt 11 and against an inwardly directed flange 10^a provided at one end of the tubular member 10, so that the bolt 11 is urged in the proper direction to maintain the same in the notch 13 provided in the post 8. The bolt 11 is provided with a finger piece 11^b whereby the same may be manipulated to draw the bolt out of engagement with the post 8 and permit the unhooking of the members 6 and 7 so that the rotatable spherical members 4 may be removed for cleansing purposes or, as such members are of magnetic material and are preferably highly magnetized, for re-magnetization when the inherent magnetic strength has been reduced and such members require re-charging. The member 5, when so detached, may likewise be cleansed and re-charged when necessary. The handle member or means C is shown as comprising a cylindrical grip portion 14, supported by end pieces 15 and 16 secured, one at each end of the member C as by screws 17, and secured at the other ends to the member 6 as by screws 18. The end piece 16 is bifurcated as at 16^a to permit central positioning of the latch bolt 11 and features pertaining thereto.

The operation, method of use and advantages of the invention will be readily understood from the foregoing description, taken in connection with the accompanying drawing and the following statement:

An operator by means of the handle means C may apply pressure to portions of the body being manipulated through the body B and the members 4 held in spaced relation therein, and by reciprocation or movement over the portions of the body of the patient being treated cause the rotation of the members 4 which being, as shown in the drawing, in staggered relation so as to thoroughly cover portions of the body being treated to be firmly pressed against the patient and by movement of the device cause circulation of the blood through the portions being treated, and, due to the inherent magnetic qualities of the members 4 and 5, beneficially influence the portions of the body being treated. When, after treatment of a patient or other use of the device, it becomes necessary to cleanse the parts of the massaging device, the latch bolt 11 may through its finger piece 11^b be moved against the compression spring 12 and the member 6 first lifted at the latched end and then unhooked by moving the same in such direction as will cause the tongue 6^b and 6^c to be withdrawn from the notches 5^b and 5^c. After such disassembling of the parts they may be separately handled and cleansed, or in case the magnetic qualities of the member 7 or the members 4 have

been lost or diminished, they may be re-magnetized and by again introducing the tongues 6^b and 6^c into their respective apertures 5^b and 5^c, after replacement of the spherical members 4 in their respective orifices or apertures, the latch bolt 11 may be again caused to engage the post 8, and the device will be in readiness for re-use.

Having thus disclosed my invention, I claim and desire to secure by Letters Patent:

1. A device of the character disclosed, comprising a body member adapted to retain in working relation and apply for massaging purposes a plurality of massaging elements, and a plurality of such massaging elements held by said body member in positions for service; said massaging elements being so arranged as to provide for massaging contact at points spaced apart in predetermined relation and consisting each of a sphere rotatably held by said body member; said body member comprising two parts between which said spheres are confined, one of such parts being provided with openings through which the spheres slightly project beyond the surface of such part; means being provided for holding said body member parts in position to so confine said spheres between the same and permitting said parts to be relatively adjusted to release said spheres; said last named means comprising a latch, and a post upon one of said parts of said body member passing through an opening in the other of said parts of said body member and with which said latch co-operates.

2. A device of the character disclosed, comprising a body member adapted to retain in working relation and apply for massaging purposes a plurality of massaging elements, and a plurality of such massaging elements held by said body member in position for service; said massaging elements being so arranged as to provide for massaging contact at points spaced apart in predetermined relation and consisting each of a sphere rotatably held by said body member; said body member comprising two parts between which said spheres are confined, one of such parts being provided with openings through which the spheres slightly project beyond the surface of such part; means being provided for holding said body member parts in position to so confine said spheres between the same and permitting said parts to be relatively adjusted to release said spheres; said last named means comprising a latch, and a post upon one of said parts of said body member passing through an opening in the other of said parts of said body member and with which said latch co-operates; said parts of said body member having hooked engagement one with the other at a point remote from said post.

3. A device of the character disclosed, comprising a body member adapted to retain in working relation and apply for massaging purposes a plurality of massaging elements, 5 and a plurality of such massaging elements held by said body member in positions for service; each of said massaging elements having an inherent magnetic quality; said body member comprising two parts between 10 which such massaging elements are confined and through one of which said massaging

elements slightly project and which latter part likewise has an inherent magnetic quality.

In testimony whereof, I have signed my 15 name to this specification in the presence of two subscribing witnesses.

OTTO JULIUS SWENSON.
